UNITED STATES PATENT OFFICE.

ERNEST RETORNAT, OF PARIS, FRANCE, ASSIGNOR TO EDMUND WRIGHT, JOSEPH WRIGHT, CHARLES S. HOWE, AND GEORGE T. MOXEY, OF PHILADELPHIA, PENNSYLVANIA, AND HARRIS FILSON, OF NEW YORK, N. Y.

UMBRELLA OR PARASOL.

SPECIFICATION forming part of Letters Patent No. 352,781, dated November 16, 1886.

Application filed July 8, 1886. Serial No. 207,413. (No model.)

To all whom it may concern:

Be it known that I, ERNEST RETORNAT, a citizen of the Republic of France, residing in Paris, France, have invented certain Improvements in Umbrellas or Parasols, of which the following is a specification.

The object of my invention is to provide an acceptable substitute for the usual bent-wire runner-retainer, such as is now used on umbrellas and parasols.

In the accompanying drawings, Figure 1 is a side view, partly in section, of part of an umbrella or parasol illustrating my invention, the ribs being closed and the tips retained by the tip-cup; Fig. 2, a similar view showing the tips released; Fig. 3, a view showing the parts in the positions which they assume in starting to raise the umbrella or parasol; Fig. 4, a view showing the runner raised to its full extent and held in this position by the retainer; Figs. 5 and 6, views illustrating a modified form of runner and retainer, and Figs. 7 and 8 perspective views of the retainers.

A represents part of the stick of an umbrella or parasol, B B portions of the ribs of the same, and D D portions of the stretchers, the latter being hung at the lower ends, as usual, to the notched and grooved flange at the upper end of a runner, F, which is in the form of a tube free to slide on the stick, this tube being retained in the elevated position shown in Fig. 4 by means of a retainer, G, and in the depressed position shown in Figs. 1 and 2 by means of a retainer, H. Usually these retainers are made of a piece of wire properly bent and secured to the stick at one end. In place of these bent wires I use sheet-metal strips, which may be punched from thin plates of sheet metal by dies of suitable shape.

Each retainer has a stem or shank, a, with bent end b, forming a spur, which is driven into the stick, in order to secure the retainer thereto, the stem a being elastic, and being expanded at the opposite end so as to project beyond the face of the stick, in order to engage with the runner.

The upper retainer, G, (shown in Fig. 4,) supports the runner by bearing against the lower end of the same in the usual manner; but the

lower retainer has a recess, d, which receives the flange at the upper end of the runner when the latter is depressed. Both retainers have slots f for the reception of transverse pins g, driven through the stick, and serving to limit both the inward and outward movement of the retainer.

The retainer may be depressed by the thumb, in order to release the runner from the control of the same, in the usual manner; but I prefer to use for this purpose a tube, J, sliding on the runner and acting upon that portion of the retainer which projects beyond the stick, so that the retainer may be depressed by a simple movement of the slide in the same direction as but in advance of the movement of the runner necessary to open or close the umbrella or parasol, that portion of the expanded head of the stem upon which the slide acts being beveled, as shown, in order to insure the depression of the retainer by the longitudinal movement of the slide.

As shown in Figs. 1, 2, and 3, the sliding tube J is cupped at the lower end to form a tip-retainer, K, the slide being first drawn downward in order to release the tips, as shown in Fig. 2, and then pushed upward in order to depress the retainer prior to the upward movement of the runner, as in Fig. 3, the cup also serving to depress the upper retainer on the downward movement of the slide when it is desired to close the umbrella or parasol. (See Fig. 4.)

In Figs. 5 and 6 I have shown the slide provided with a simple swell or enlargement at the lower end, to form a convenient means of manipulating the slide and to expand the lower ends of the ribs preparatory to the raising of the umbrella or parasol.

The upper retainer (shown in Fig. 6) is notched for engagement with a slotted runner, instead of retaining the runner by contact with the lower edge of the same, as in Fig. 4.

My improved retainer is stronger and generally more acceptable than the usual bent-wire retainer, and said improved retainer can be manufactured as rapidly and cheaply as a wire retainer, the latter having to be bent into proper form, while my improved retainer, with

its holding-spur and slot for the stop-pin, can be punched from a sheet of metal at one operation.

I do not claim, broadly, a runner-retainer made of sheet metal, as this has been heretofore proposed; but

I claim as my invention—

The combination of the stick having a transverse stop-pin with a runner-retainer, consisting of a strip of sheet metal having an elastic shank with spur for holding the same at one

end, and at the opposite end an enlarged head for engagement with the runner, said head having a slot for the reception of the stop-pin, all substantially as specified.

In testimony whereof I have signed my name to this specification in the presence of two subscribing witnesses.

ERNEST RETORNAT.
